UNITED STATES PATENT OFFICE.

WILLIAM EDWARD ARMSTRONG, OF BELFAST, IRELAND, ASSIGNOR TO HARLAND & WOLFF, LIMITED, OF BELFAST, IRELAND.

APPARATUS FOR RAISING, LOWERING, AND STORING SHIPS' BOATS.

1,090,962.

Specification of Letters Patent. Patented Mar. 24, 1914.

Application filed April 18, 1913. Serial No. 762,081.

To all whom it may concern:

Be it known that I, WILLIAM EDWARD ARMSTRONG, a subject of the King of Great Britain, residing at the Queen's Island Ship-
5 building and Engineering Works, Belfast, Ireland, have invented new and useful Im-
provements in Apparatus for Raising, Low-
ering, and Storing Ships' Boats, of which
the following is a specification.

10 The object of this invention is to enable
a boat to be lowered from or raised onto a
ship on an even keel in spite of the ship be-
ing down by the head or stern.

15 The ropes by which a ship's boat is sus-
pended are commonly wound on two co-
axial drums, means being provided for si-
multaneously revolving the drums. Accord-
ing to this invention such drums are con-
nected and locked together by a worm and
20 worm wheel so that they normally revolve
together but can be revolved relatively to
each other by turning the worm.

25 In the accompanying drawings:—Figure
1 is a plan view of apparatus constructed
in accordance with this invention. Fig. 2
is an end elevation thereof, and Fig. 3 is a
longitudinal section of the same.

a and *b* are the two drums. The drum *a*

is fixed to a shaft *c* to which is also fixed a
spur wheel *d* gearing with a pinion *e* on a 30
shaft *f* which is driven in any convenient
manner. The drum *b* is fixed to a sleeve *g*
on the shaft *c*. This sleeve has fixed to it a
bracket *h* carrying a worm *j* gearing with a
worm wheel *k* keyed on the shaft *c*. Nor- 35
mally therefore the drums *a* and *b* are
locked together and are driven simulta-
neously by rotating the shaft *f*, but by turn-
ing the worm *j* the drums can be rotated
relatively to each other until the boat is on 40
an even keel.

I claim as my invention,

1. The combination of a pair of drums,
a worm and worm wheel normally locking
the drums together and means for simulta- 45
neously rotating the drums.

2. The combination of a shaft, a drum
fixed to the shaft, a sleeve on the shaft, a
drum fixed to the sleeve, a worm and worm
wheel normally locking the sleeve to the 50
shaft and means for rotating the shaft.

WILLIAM EDWARD ARMSTRONG.
